UNITED STATES PATENT OFFICE.

AUGUSTUS F. W. MACMANUS, OF THE UNITED STATES ARMY.

FLYING-MACHINE EQUILIBRIUM APPARATUS.

1,002,067.

Specification of Letters Patent. Patented Aug. 29, 1911.

Application filed December 10, 1909. Serial No. 532,419.

To all whom it may concern:

Be it known that I, AUGUSTUS F. W. MACMANUS, of the United States Army, a citizen of the United States, have invented new and useful Improvements in Flying-Machine Equilibrium Apparatus, of which the following is a specification.

This invention relates to electrically operated mechanism for controlling the equilibrium of aeroplanes, flying machines, airships, and similar machines.

It is generally applicable to all forms of power driven machines for aerial navigation in which propellers driven by engines or other sources of energy carried by the machine are relied upon to give motive force to overcome air resistance, and where alterations of equilibrium occur due to steering strains, shifting of load, and variations in air pressure from various causes tend to vary the normal center of gravity, or tilt and derange the relative normal navigating position of the machine in the air. When applied to such machines under the above conditions, the invention operates to restore normal conditions, overcomes defective equilibrium and retains the machine under all conditions in its proper relative navigating position.

As the invention is especially applicable to well known forms of aeroplanes, it will be described and illustrated in connection therewith, but it will be understood that it is not intended thereby to limit the use of the invention to the forms shown or to this class of machines alone.

The invention consists in providing automatic electrically operated mechanism whereby unusual or abnormal conditions of equilibrium in an aeroplane or similar device are restored to normal, and combining with such mechanism a controlling device operated automatically by the tilting of the machine to actuate the electrically operated mechanism.

More specifically it consists in providing a machine of the kind described, with a series of propellers or similar devices appropriately placed to exert pressure to reestablish equilibrium when rotated, providing separate driving means for each of the series of propellers, and governing the operation of the driving means by a control mechanism for automatically selecting and operatively connecting the driving mecha-

nism in accordance with the variation from normal equilibrium of the machine.

The invention consists specifically in the arrangement of propellers, whereby equilibrium is restored in relation to the planes of the aeroplane, and the arrangement and construction of the controlling device whereby they are operated, and in general in the details of construction and arrangement described in detail in the following specification, and further defined in the following claims.

In the accompanying drawings: Figure 1 is a perspective outline of a Wright biplane flying machine provided with propellers and a controlling device arranged in accordance with my invention, the electrical connections on account of the small scale being omitted. Fig. 2 is a perspective diagram illustrating a different arrangement of propellers. Fig. 3 is a similar perspective view illustrating a third arrangement of propellers. Fig. 4 is a side elevation of the controlling device. Figs. 5 and 6 are detail sections on similarly numbered lines on Fig. 4, looking in the direction of the arrow. Fig. 7 is a side elevation of a modified form of the controlling device. Fig. 8 is a bottom plan of Fig. 7 with parts broken away. Fig. 9 is a diagram showing the controlling circuit for a plane provided with two fans. Fig. 10 is a diagram of a Curtiss biplane in which the means for generating the controlling current is directly coupled to the engine, and Fig. 11 is a plan view of a Bleriot monoplane with extension frames provided with equilibrium devices in accordance with my invention.

Referring to the drawings, A indicates an aeroplane comprising upper and lower planes B, B', vertical control planes C, C' and a horizontal control or steering rudder D. These parts are connected and supported by a suitable frame E and the machine is driven or propelled by an engine or motor F connected to a driving propeller or propellers G.

In Fig. 1 I have omitted the motor and driving propeller, which are shown in Figs. 10 and 11.

A series of small fans or propellers 1, 2, 3, 4 are mounted on the machine and are preferably arranged as shown in Fig. 1, that is, beneath the ends of the main planes B', and under the vertical control planes C, and steering planes D. These propellers

are arranged horizontally and are driven by small electric motors H furnished with power by a centrally located storage battery or other source of electric energy I carried by the machine. Each of the motors H is separately connected to the source of energy—is normally inactive and operated by a control mechanism J operated by abnormal displacement or tilting action of the machine in its movement through the air to properly select and connect the different motors and rotate the propellers in such manner as to set up pressure in opposition to the displacement or tilt of the machine. 10 Various arrangements of these propellers or fans may be adopted, as for instance those shown in diagram in Figs. 2 and 3 where the fans are arranged both above and below the main planes and vertical control 15 planes in which case the upper fans are rotated to exert downward pressure on said planes while the lower fans are arranged to exert an upward pressure. And the connections are so arranged that the fans in opposite corners of the planes act in pairs to restore equilibrium as indicated by the arrows in Figs. 2 and 3.

It is obvious that the fans should be placed as far as possible from the center 20 of the machine in order to exert the greatest leverage. In machines of small superficial area this leverage may be increased by mounting the fans on extensions K, K, built out from the frame of the air machine as 25 shown in diagram in the machine of the Bleriot type illustrated in Fig. 11.

The mechanism for automatically controlling the operation of the fans 1, 2 and 3 and 30 4 through the motors H and for establishing connection with the battery or other 40 source of energy I consists as shown in Figs. 4, 5 and 6 of a freely suspended pendulum L depending from a base or support M to which it is connected by a ring L. The 45 pendulum by its swinging motion is adapted to operate circuit closing devices operating to close circuits including the motors H and the battery I, as indicated in diagram in Fig. 9.

50 The circuit closing devices consist of levers N pivotally secured to depending bars O, mounted on the base M adjacent to the pendulum L. The outer ends of the levers N are provided with contact screws n 55 adapted to make connection with angular anvil blocks P, mounted on the base M. The anvil blocks P are provided with guiding jaws p of insulating material adapted to receive the outer ends of the levers N to 60 prevent their lateral displacement and to insure proper contact between the screws n and the anvil blocks P. The anvil blocks also carry depending arms or brackets p' 65 extending behind the levers N. Said arms being provided with back stop screws p'',

which are utilized to hold the anvil blocks in position relative to the levers N, and 70 a tilting screw Q being adjusted to

insulated from the arms N by blocks N* by which motion of the levers in breaking contact is limited and adjusted. The weight of the levers N is partially sustained by springs n¹ attached at one end to the depending 75 bars O, and at their other ends provided with adjusting screws n², passing through the levers, whereby their tension may be regulated, and the consequent force required to operate the levers changed or varied. 75

The levers N are operated to make contact by elbow levers Q, pivoted at their lower ends to the lower ends of the depending bars O, and interposed between the said bars and the pendulum L. The upper 80 ends of the elbow levers are provided with cheek plates q, which embrace the short ends of the levers N, and thereby retain the two members in operative relation, and with blocks q' against which the pendulum 85 L strikes to rock the levers on their pivots and thereby actuate the levers N to make contact.

It is to be understood that the number of contact levers provided, will be the same as the number of motors and fans to be controlled. The relative arrangement of the controlling members in relation to the planes of the machine, being such that one pair of control levers is in line with, or coincident with the line of flight and the second pair at right angles thereto. If only one pair of fans are to be controlled the levers will be arranged in a line at right angles to the line of flight. 100

As will be seen by reference to Fig. 9, the connections necessary to control the motors and fans are very simple. The pendulum L is connected to one pole of a source of energy, in this case a storage battery I and each of the anvils represented in the diagram by the stop screws S, S, connected to a loop passing through the motor armature and connected to the opposite pole of the battery I. It will be readily understood that there must be as many loops as the number of fans to be controlled, and that the relative arrangement will be varied to meet various conditions. Instead of the battery I shown in Fig. 9, a dynamo T as shown in Figs. 10 and 11 may be utilized to furnish the current necessary to operate the motors, in which case I prefer to connect the dynamo or the armature of the dynamo directly to the shaft of the engine which furnishes the motive power for driving the machine, as shown in Fig. 10, the connections being similar in each form. 110

It is obvious that many variations may be made in the arrangement of the parts, and also in the construction of the controlling mechanism. One such variation is illustrated in Figs. 7 and 8 of the drawings, in which the pivoted levers N on the previously described construction are replaced by springs 125

which are utilized to hold the anvil blocks in position relative to the levers N, and a tilting screw Q being adjusted to

U adapted to make contact and close circuits through contact screws V carried in brackets v' secured to the supporting base. The operation of this device is similar to the one 5 previously described.

In the application of the invention to a Curtiss biplane machine shown in Fig. 10, in which B² are the ailerons for manual lateral control, and in which I have shown the dynamo T directly connected with the shaft of the motor F as before described, the fans 1, 10 2, 3 and 4 are arranged, above the ends of the main plane B and controls C and D instead of below these parts as shown in Fig. 1.

Many other modifications will occur to the skilled mechanic, fully within the scope of the invention. For instance the fans might be driven by power shafts connected to the 20 engine which drives the machine, and electrically controlled clutch mechanism used for connecting the fans to the power shaft, the clutch controlling devices being actuated by the pendulum and contact devices in a 25 precisely similar manner to their present use. The controlling device may be located in any convenient position on the planes of the machine, but should be near the center and is preferably located in a biplane under 30 the center of the upper plane as shown.

It will be understood that the fans may be located to meet conditions, although the preferred location is shown in the drawings.

Having thus described my invention what 35 I claim and desire to secure by Letters-Patent is:—

1. In an aeroplane or similar mechanism, propellers arranged to control the tilting motion of the aeroplane in one general direction, motor mechanism for driving said 40 propellers, electric circuits controlling said motor mechanism, pivotally mounted circuit closing levers, pivotally mounted operating

levers for actuating said circuit closing levers, and a controlling device influenced by 45 the reverse tilting motions of the aeroplane in said general direction for actuating one or the other of said operating levers.

2. In a flying machine controlling mechanism of the kind described, a main supporting plane, a horizontal rudder, a vertical rudder, fans arranged adjacent the extremities of the main plane, fans mounted in the line of flight adjacent the vertical and horizontal rudders, motors whereby said fans 50 55 may be operated to direct blasts of air against said adjacent parts to oppose tilting motion of the machine, normally open circuits leading from said motors to a source of energy, contacts included in said circuits by 60 which they may be closed to operate said motors and drive said fans, and a pendulum actuated by the tilt or displacement of the machine to select and operatively connect through said contacts one or more of said 65 motors and thereby oppose said displacement and restore equilibrium.

3. A circuit closing device adapted to be operated by the tilting of an air ship, aeroplane or similar machine, said circuit closing device comprising a freely suspended pendulum, a series of contact operating levers adapted to be operated by the movements of said pendulum, contacts adapted to be closed by the movements of said levers, 70 and intermediate levers interposed between the pendulum and contact levers whereby relatively slight motion in the pendulum is multiplied in the circuit closing devices.

In testimony whereof I affix my signature 80 in presence of two witnesses.

AUGUSTUS F. W. MACMANUS.
